UNITED STATES PATENT OFFICE.

JOHN A. MACDOWELL, OF ST. LOUIS, MISSOURI.

BAFFLE-WALL BLOCK.

Application filed April 9, 1926. Serial No. 101,008.

2 This invention is a baffle wall block or tile for use in building the usual baffle walls in water tube boilers.

3 An object of the invention is to provide 5 a baffle wall block or tile having semi-circular or arcuate cut-outs at two of its opposite edges and having its other two opposite and parallel edges beveled off at opposite faces of the block to form laps, so 10 that when a plurality of such blocks are assembled to form the said baffle wall between the water tubes, the semi-circular cut-outs will embrace and surround in a lateral direction adjacent water tubes, while the 15 beveled edges of the blocks will vertically overlap one another.

4 Another object is to provide a baffle wall block or tile having semi-circular cut-outs 20 at opposite edges adapted to embrace the water tubes of the boiler for the purpose of forming a complete baffle wall with a plurality of such blocks, the said semi-circular edges of each block being lined or coated with a fusible substance such as 25 pitch, tar or wax, to the end that after the baffle wall is completed, the heat within the boiler may fuse and melt away the said fusible lining, leaving slight clearance spaces between the edges of the blocks and 30 the water tubes, the said clearance spaces serving to facilitate the removal and replacement of the water tubes without damaging the said baffle wall.

5 Another object is to provide a baffle wall block or tile having two opposite edges thereof beveled off at opposite faces of the block, so that when a plurality of such blocks are assembled for completing a baffle wall transversely of the water tubes of a 40 boiler, the said blocks will overlap one another vertically, in a shingle-like relation, to the end that by building two such walls in parallel spaced relation, with the laps of the blocks directed inwardly from top to bottom, a plastic clay or other viscous material may be filled in between the two walls from the top, for the purpose of 45 completing a continuous solid structure, without danger of the plastic filler working out laterally between the blocks, and water tubes of the boiler.

6 In the drawing—

7 Figure 1 is a side view of one of the tiles or blocks;

8 Figure 2 is an edge view of the same; 55 Figure 3 is a sectional view of a portion

of a baffle wall constructed of this form of block or tile, including a sectional view of several water tubes extended through the wall.

60

Figure 4 is an edge view showing the bevel of the laps reversed as to the form shown in Figure 2.

7 This invention consists simply in the tile 1, having the semi-circular cut-outs 2 at 65 opposite edges thereof, and having the other two opposite edges beveled off at opposite faces of the tile, as shown at 3 and 4 to form laps. The cut-outs 2 are adapted to laterally engage the water tubes 5 and 70 half encircle the same, when the tile is positioned transversely between the said tubes, and of course the tile is made of just the right dimensions to span the horizontal and vertical distances between the tubes. So 75 formed, a plurality of such tiles may be mounted in place one over the other from top to bottom of the "alleys" between the water tubes, with the beveled edges of the tiles vertically overlapping each other as 80 shown at 6 in Figure 3, thereby forming a complete baffle wall or shell 7. Two of such walls or shells 7 may be constructed in parallel spaced relation, with the lower laps 3 of each successive tile from top to 85 bottom, directed inwardly and overlapping the upper laps 4 of the next lower tiles; and any desired viscous or plastic filler (not shown) may then be poured in at the top 90 of the structure and allowed to flow down and fill the spaces between the two said shells. Owing to the inwardly directed, overlapping relation of the tiles, the plastic 95 filler will not work out between the tiles. Of course, the tiles should be accurately positioned in parallel transverse planes, and the baffle walls may be built perpendicularly to the tubes or they may be inclined from top to bottom, relative to the tubes, as shown in Figure 3. In the latter event the edges 100 of the semi-circular cut-outs 2 would of course be correspondingly inclined at top and bottom as shown at 8, so as to stand at all points in parallel relation to the walls of the tubes. The edges of the cut out 105 portions 2 may be lined or coated as shown at 9 with any suitable fusible substance, such as pitch, tar or wax, and in that case the cut-outs 2 would be sufficiently larger than the exterior diameter of the tubes 5, 110 to enable a coating of substantial thickness to be incorporated upon the said edges,

without crowding too closely upon the walls of the tubes when the tiles are mounted in position. With the tiles so coated at the edges embracing the tubes, the heat passing through the boiler would serve to fuse or melt the said fusible coatings after the baffle walls were in operation, and thus clearance spaces would be left between the edges of the tiles and the walls of the tubes, which spaces would be of use in facilitating the removal and reinsertion of water tubes, without disturbing or injuring the said baffle walls.

While I have herein described a certain specific manner and method of constructing and assembling the elements of my invention, it is understood that I may vary from the same in minor details, not departing from the spirit of my invention, so as best 20 to construct a practical device for the purpose intended, as defined in the appended claims.

In order to facilitate the use of the form of tile referred to herein, in the building or repair of baffle walls as described, I have designed a special tool for handling and inserting the tiles in place in the wall, which tool is the subject matter of a separate application for patent.

30 I claim:—

1. In combination with the water tubes of a boiler, a baffle tile for mounting transversely therein between, the said tile having arcuate cut-outs at two of its opposite edges to laterally engage adjacent water

tubes, the said cut-outs being lined with fusible coatings.

2. In combination with the water tubes of a boiler, a baffle tile for mounting transversely therein between, the said tile having 40 arcuate cut-outs at two of its opposite edges and having its other two opposite and parallel edges beveled off at the opposite faces of the tile to form laps; the said cut-outs being lined with a fusible substance and being adapted to laterally engage adjacent water tubes, the said laps being adapted to vertically engage and overlap similar laps of the tiles positioned above and below in a common plane.

3. The method of constructing two walls in spaced parallel relation across a bank of boiler tubes for the purpose of placing a plastic, siccative material therebetween without danger of the plastic material working out between the blocks composing the wall and the tubes; the said method consisting in providing a plurality of tiles having arcuate cut-outs at their opposite edges adapted to laterally engage adjacent water tubes, and having their two remaining opposite and parallel edges beveled off at the opposite faces of the tiles to form laps adapted to vertically engage and overlap similar laps of adjacent tiles, then lining 60 the said arcuate cut-outs with a fusible substance; and then building the said spaced walls with the said tiles.

In testimony whereof I affix my signature.

JOHN A. MACDOWELL.
